Nelson W. Howard

UNITED STATES PATENT OFFICE.

FRANK W. CHRISTY, OF BEVERLY, MASSACHUSETTS, ASSIGNOR TO UNITED SHOE MACHINERY CORPORATION, OF PATERSON, NEW JERSEY, A CORPORATION OF NEW JERSEY.

SKIVING MACHINE.

Application filed August 24, 1923. Serial No. 659,173.

To all whom it may concern:

Be it known that I, FRANK W. CHRISTY, a citizen of the United States, residing at Beverly, in the county of Essex and State 5 of Massachusetts, have invented certain Improvements in Skiving Machines, of which the following description, in connection with the accompanying drawings, is a specification, like reference characters on the 10 drawings indicating like parts in the several figures.

This invention relates to skiving machines and is herein illustrated as embodied in a machine for skiving the edges of pieces of 15 upper leather for use in the manufacture of boots and shoes.

In the process of manufacturing boots and shoes it is customary to skive the edges of vamps, tips and other shoe parts; and 20 in order to meet various conditions it is necessary that means be provided for producing scarfs of different widths and inclinations. Skiving machines commonly comprise a knife, a feed roll and a presser- 25 foot; and the angle of the scarf has been varied in different ways, for example, by providing interchangeable presser-feet of different contours or by adjusting the presser-foot into different angular positions. 30 With a machine having interchangeable presser-feet it is possible to change with precision from one type of scarf to another, but the change causes delay, and the provision of a plurality of presser-feet involves 35 considerable expense. On the other hand, in a machine in which the presser-foot is angularly adjustable, it is difficult to change with rapidity and precision from one type of scarf to another. If, for example, the 40 presser-foot is set to produce a three-eighths inch scarf and it is desired to change to a three-quarters inch scarf, it is necessary to proceed by the method of trial and error to adjust the presser-foot; and here again 45 time is wasted.

By the present invention a plurality of stop surfaces are provided, one for each desired type of scarf, any one of which may be rendered operative to determine the position in which the presser-foot shall be held. The illustrative machine is provided

with a rotary disk knife, a feed roll which is yieldable bodily, and angularly, and a presser-foot which is adjustable about a pivot to determine the width and inclination 55 of the scarf which shall be produced. Co-operating with the presser-foot in such manner that any one of them may be rendered operative are a plurality of stops, each stop corresponding to a particular position of the foot and consequently to a scarf of a certain inclination. With such a construction the operator may change rapidly and accurately from a scarf of one inclination to that of another merely by 60 rendering one stop inoperative and another one operative.

This and other features of the invention, including certain details of construction and combinations of parts, will be described as embodied in an illustrative machine and pointed out in the appended 70 claims.

Referring now to the accompanying drawings;

Figure 1 is a perspective of a portion of a machine, in which the present invention is embodied;

Fig. 2 is a perspective of the presser-foot and its support;

Fig. 3 is a detail partly in section and partly in elevation of a portion of the foot and one of the abutments;

Fig. 4 is an elevation of a modified form; and

Fig. 5 is a plan of the stop members of the modified form.

Referring first to Figures 1 to 3 inclusive, the frame 7 of the machine is provided with a substantially flat top through 90 a slot in which the upper portion of a cylindrical feed roll 9 projects; and co-operating with the roll is a rotary disk knife 11 mounted at the upper end of an upright shaft, not shown. The roll is normally 95 held in the position shown by springs which permit it to be pressed down bodily in a vertical path and also to swing or tilt endwise. In the operation of the machine, the roll and knife are rotated continuously; 100 and the angle of the scarf produced is determined by the angular position to which

the presser-foot 13 is adjusted, the roll, by reason of its yielding mounting, accommodating its position to that of the presser-foot. Any suitable mechanisms may be provided for rotating the knife and roll and for mounting the roll so that it may yield away from the knife to provide for different thicknesses of work and angularly to provide for scarfs of different widths and 10 inclinations, such, for example, as those shown in the patents to Harmon, No. 1,161,860 and Hirth, No. 854,500. It has been thought not necessary to illustrate these mechanisms since in general they are old 15 and well-known, it being common practice to provide a rotary knife, a feed roll yieldable bodily and angularly and an adjustable presser-foot the position of which determines the inclination of the scarf.

20 The presser-foot 13 is pivoted at 15 to a finger 17 formed at the outer end of a bracket 117, said bracket being adjustably fastened to the table of the machine by a cap-screw 19 which passes through a slot 25 in the bracket and is threaded into the table. A guide rib 217 formed on the under side of the bracket fits in a guideway (not shown) in the table to ensure that adjustment of the bracket shall take place in a direction trans- 25 verse to the line of feed movement of the work. Fastened to the body portion of the bracket 117 parallel to and spaced from the finger 17 is a second finger 21, the tail 113 of the presser-foot 13 being adapted to swing 30 vertically in the space thus provided. A leaf-spring 23, fastened at one end to the bracket, bears downwardly with its free end against the top of a pin 25 carried by the tail of the presser-foot 13 and tends at all times 35 to swing the tail 113 downwardly and thereby to swing the presser-foot proper 13 upwardly about the pivot 15. In order to determine the position in which the presser-foot shall be held by the spring, a plurality of adjustable stops in the form of thumb-screws 27 are provided which are threaded through the tail of the presser-foot. Adapted to co- 40 operate selectively with the lower ends of the stop-screws are a plurality of abutments in the form of pins. Each abutment (see Fig. 3) has a head 31 adapted to slide through a hole in the finger 21, said head being carried at one end of a slender stem 33 which slides through a hole in the vertical plate of 45 an angular bracket 35, the horizontal plate of which is fastened by screws 37 to the stationary finger 21. Surrounding the stem 33 of each abutment and located between the head 31 and the vertical plate of the angular bracket 35 is a coiled spring 37 which tends at all times to urge the head 31 into position beneath the lower end of the corresponding stop-screw 113. In order to permit the abutment to be held in operative or in- 50 operative position as may be desired, each 55

stem 33 has fast to its outer end a knurled head 39 having integral with it a slender finger 41 which may be caused either to contact with the vertical plate of the angular bracket 35 or to enter a hole 43 in said plate 70 as may be desired. As long as the finger contacts with the plate, the abutment remains in inoperative position. When the finger is moved into register with the hole provided for it, the spring 37 moves the 75 abutment into operative position to engage the lower end of its corresponding stop-screw 27 and thereby to determine the angular position in which the leaf-spring 23 shall hold the presser-foot. 80

In the illustrative machine four stops 27 are provided. Assuming for convenience of description that the first stop (the right-hand one as viewed in Fig. 1) has been adjusted to produce a scarf one inch in width 85 and the succeeding three to produce scarfs of three-quarter, one-half and one-quarter inches respectively, it will be seen that the operator may change with rapidity and precision from any one width of scarf to any other by moving whatever abutment is in 90 operative position into inoperative position and moving the desired abutment into operative position. In doing this it may be necessary to press down the operative portion of 95 the presser-foot 13 so as to raise temporarily the tail of the presser-foot against the action of the leaf-spring 23. As illustrated the third abutment (counting from the right in Fig. 1) is operative, and a scarf one-half 100 an inch in width would be produced on the work. If now it is desired to produce a scarf one inch in width, the first abutment is rendered operative and the third one withdrawn to inoperative position. 105

Referring to Figures 4 and 5, wherein a modified construction is shown, the knife 11 and roll 9 are exactly the same as in Fig. 1. The presser-foot 53 is pivoted at 55 to a bracket 57 and has threaded through its tail 153 a screw 59 the lower end of which is held in contact with any selected one of four stops, presently to be described, by a leaf-spring 61 the lower end of which is fastened by a screw 63 to the stationary 115 bracket 57 and the free upper end of which bears against the tail of the presser-foot. Located on the bracket is a disk-shaped carrier 65, said carrier being rotatably mounted on the upper smooth portion of a screw 67, the lower reduced portion of which is threaded into the bracket. Pivoted on the carrier are a plurality of stops, four being shown in the illustrative construction. Each stop 69 is pivoted at 71 to the carrier 120 and is urged at all times to swing outwardly about its pivot by a coiled spring 73 which is located in a socket in the stop and bears at one end against the bottom of 125 the socket and at the other end against the 130

carrier 65. A screw 75 passes through a bore in each stop and through the coils of each spring and is threaded into the carrier. By turning any selected screw, the stop with which it is associated may be adjusted about its pivot. Formed in the upper face of each stop 69 is a V-shaped groove 77 the depth of which increases from its narrow to its wide end, as shown best in Fig. 4; and with the bottom of one of these grooves the lower end of the screw 59 in the tail of the presser-foot is designed to contact during a skiving operation. The locality on the bottom of any groove 77 which will be engaged by the end of the screw 59 will depend upon the angular position into which the particular stop, in which the groove is formed, has been adjusted by turning the proper adjusting screw 75. In the figures three of the stops occupy the same angular position with respect to the carrier 65; but in practice all four will usually be adjusted into different angular positions so as to be effective to hold the presser-foot in four different positions. In the operation of the machine, when it is desired to change from a scarf of one inclination to one of a different inclination, all that is necessary is to rotate the carrier to bring the desired stop into position beneath the screw 59, the sides of the groove 77 being inclined upwardly and outwardly so that the rounded lower end of the screw 59 will ride out of one groove and into the next one when the carrier is rotated.

In the form shown in Figs. 1 to 3, the edge gage 81 has a stem which extends into a socket in the finger 21 and is adjustably held in position by a set-screw 83. In the form shown in Figs. 4 and 5, the edge gage 85 is shown in section and may be adjustably mounted in any suitable manner.

Having thus described my invention, what I claim as new and desire to secure by Letters Patent of the United States is:—

1. A machine of the class described having, in combination, a knife, a feed roll, an adjustable presser-foot adapted to hold the work against the roll and by its position to determine the character of the scarf produced, and means including a plurality of stop surfaces each corresponding to a scarf of predetermined character for determining the position which the foot shall occupy.

2. A machine of the class described having, in combination, a knife, a feed roll, an adjustable presser-foot adapted to hold the work against the roll and by its position to determine the character of the scarf produced, a spring tending at all times to urge the foot toward one limit of its adjustment and means acting in opposition to the spring and including a plurality of stop surfaces each corresponding to a scarf of a predetermined character for determining

the position in which the foot shall be held by the spring.

3. A machine of the class described having, in combination, a knife, a feed roll, an adjustable presser-foot adapted to hold the work against the roll and by its position to determine the length and inclination of the scarf produced, and a series of stops for the foot each stop corresponding to a selected position of the foot, and means whereby a selected stop may be rendered operative.

4. A machine of the class described having, in combination, a knife, a feed roll, a pivoted presser-foot adapted to hold the work against the roll and by its position to determine the length and inclination of the scarf produced, and a series of stops for the foot each stop corresponding to a selected position of the foot, and means whereby a selected stop may be rendered operative.

5. A machine of the class described having, in combination, a knife, a feed roll, an adjustable presser-foot adapted to hold the work against the roll and by its position to determine the length and inclination of the scarf produced, and a series of stops for the foot each stop corresponding to a selected position of the foot, means whereby the stops may be adjusted to vary the selected positions as desired, and means whereby a selected stop may be rendered operative.

6. A machine of the class described having, in combination, a knife, a feed roll, an adjustable presser-foot, a stationary member to which the foot is pivoted, means tending at all times to urge the foot about its pivot toward one limit of its adjustment, and a plurality of stops any selected one of which may be moved into position to determine the position in which the foot shall be held.

7. A machine of the class described having, in combination, a knife, a feed roll, an adjustable presser-foot adapted to hold the work against the roll and by its position determine the character of the scarf which will be produced, a spring tending at all times to move the foot toward one limit of its adjustment, and a plurality of stops any one of which may be rendered operative to determine the position in which the foot shall be held by the spring.

8. A machine of the class described having in combination, a knife, a feed roll, an angularly adjustable presser-foot adapted to hold the work against the roll and by its position determine the character of the scarf which will be produced, a spring tending at all times to tilt the foot toward one limit of its adjustment, and a plurality of stops any one of which may be rendered operative to determine the position in which the foot shall be held by the spring.

9. A machine of the class described hav-

ing, in combination, a rotary disk knife, a cylindrical feed roll, an angularly adjustable presser-foot adapted to hold the work against the roll and by its position to determine the character of the scarf produced, a spring tending at all times to move the foot toward one limit of its adjustment, and

a plurality of stops any one of which may be rendered operative to determine the position in which the foot shall be held by the spring.

In testimony whereof I have signed my name to this specification.

FRANK W. CHRISTY.
